UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

SHEET-FEEDING APPARATUS.

1,086,352.

Specification of Letters Patent. Patented Feb. 10, 1914.

Application filed July 23, 1913. Serial No. 780,643.

To all whom it may concern:

Be it known that I, ALBERT B. DICK, a citizen of the United States, residing at Lake Forest, in the county of Lake and State of Illinois, have invented certain new and useful Improvements in Sheet-Feeding Apparatus, of which the following is a specification.

This invention relates to sheet-feeding apparatus for feeding sheets successively to a machine for printing, folding or otherwise acting upon the sheets.

The invention relates more particularly to apparatus of this character of the type shown in United States Letters Patent No. 1,054,637 granted to me February 25, 1913.

The object of the invention is to effect certain improvements in apparatus of the character shown in the above-mentioned patent to the end that the apparatus is made more convenient to use and is more accurate and reliable in its operation.

One feature of the invention resides in the provision of certain tension-adjusting means for regulating the tension between the feeder-roller and the roller which coacts with the upper surface of the feeder-roller to forward a sheet after the edge of the sheet has been buckled by the feeder and carried around upon the upper surface of the feeder.

Another feature of the invention resides in the provision of an improved form of feed-board. This involves making the feed-board in two parts one of which is stationary mounted while the other of which is pivoted so as to rock upon an axis close to the adjacent edges of the two parts of the feed-board. In this way the up and down movement of that portion of the sheet-pile which coacts with the feeder can be effected without moving the entire feed-board and the entire pile thereon with the result that a saving in power is effected and the operation of the machine is made more smooth.

Another feature of the invention resides in the provision of guides on the feed-board for coaction with the edges of the sheet-pile, which guides are movable to various positions, but are always maintained in a definite angular relation to the edges of the feed-board. This construction facilitates positioning the sheet-pile and makes the machine more convenient to use.

55 The preferred embodiment of the inven-

tion is illustrated in the accompanying drawings in which—

Figure 1 is a central section of a sheet-feeding apparatus, Fig. 2 is an elevation partly in section of one of the parts of the feed-board, Fig. 3 is a top view of the same, Fig. 4 is an edge view of the same and Fig. 5 is a detail sectional view of one of the guides.

Referring to the accompanying drawings, I have illustrated my improved form of sheet-feeding apparatus as used in connection with a stencil-duplicating machine. This machine includes a stencil-carrying drum 6 and a pressure roller 7 coacting therewith and the sheets fed by the sheet-feeding apparatus are passed between the drum and pressure roller which print upon the sheets and forward the sheets between them. The drum and pressure roller and sheet-feeding apparatus are mounted upon side frames 8 which are secured upon a base 9.

The sheet-feeding apparatus comprises a feed-board and a rotatable feed-roller overlying the forward end of the feed-board and adapted to coact with the top sheet of the pile to buckle the forward edge of that sheet and then feed said edge over the upper surface of the feeder-roller. The feeder-roller is shown at 10, it being preferably of sectional form with the several sections mounted upon a shaft 11 which is journaled for rotation in bearings formed in the side frames 8. The feed-board consists of two parts mounted edge to edge and one relatively stationary while the other is pivotally mounted. The stationary part of the feed-board consists of a board 12 which is supported upon two rods 13 and 14 extending between the side frames. For this purpose the board 12 has sheet metal strips 15 secured to its under side and bent to the configuration shown so they will coact with the rods 13 and 14 to hold the board 12 removably in the position in which it is shown in Fig. 1. The other part of the feed-board consists of a piece of sheet-metal 16 having ears 17 secured thereto which ears are adapted to turn about the rod 14. As will be seen the edge of the plate 16 is close to the edge of the board 12 and the upper surfaces of these two parts are in substantially the same plane. The plate 16 is, however, adapted to rock about the axis of the rod 110

14, which is located close to the adjacent edges of the parts 12 and 16 of the feed-board. The plate 16 is rocked by a cam 18 mounted on a shaft 19 which is rotated by the mechanism employed for rotating the drum 6. This cam 18 actuates a lever having an arm 20 carrying a roller which rides on the surface of the cam. This lever is secured to a shaft 21 adapted to rock in bearings in the side frames of the machine. Another arm 22 of the lever carries a pin 23 which is received in a slot formed in a piece 24 secured to the under side of the plate 16. A coiled spring 25 is secured to a suitable 10 abutment 26 and to another arm 27 of the lever above mentioned.

A stop for the forward edge of the sheets of the feed-board is shown diagrammatically at 28.

20 Above the feeder-roller 10 is a roller 29 which coacts with the feeder-roller to forward a sheet between the two. The shaft of roller 29 is carried by arms 30 secured to a rock-shaft 31 extending between the side 25 frames of the machine and one end of this shaft has an arm 32 secured thereto carrying a roller which is adapted to ride on the periphery of a cam 33 which is secured to shaft 19. A spring 34 holds the roller always in engagement with the cam. By this mechanism the roller 29 may be moved upwardly to the position in which it is shown in Fig. 1, or downwardly to a position in which it coacts with the feeder-roller 10 30 through a sheet. The tension with which the roller 29 bears against the roller 10 through a sheet is made adjustable. I have found that when it is possible to regulate the pressure between these two rollers, more 35 efficient and reliable results may be obtained, with paper of different weights. This adjustment is effected by means of a cap 35 which is interiorly threaded to receive the threaded upper end of a pin 36 to whose 40 lower end the spring 34 is secured.

In the operation of the machine a pile 50 of sheets is placed upon the feed-board consisting of parts 12 and 16, with the forward edge of the pile against the stop 28. During each rotation of the drum 6 the cam 18 is rotated and this causes the part 16 of the feed-board to be rocked downwardly and back. In this downward movement the pile 55 is carried out of coaction with the feeder 10 and on the upward movement the top sheet of the pile is carried into contact with feeder 10. The feeder, turning in the direction of the arrow thereon, draws the edge of the top sheet back from stop 28 and buckles 60 that sheet in rear of the roller. As the edge of the sheet passes from under roller 10, the fluted surface of the roller catches the edge of the sheet and carries that edge around upon the top surface of the feeder 10. Immediately after the feeder engages the edge

of the sheet in this manner the pile is lowered away from the feeder. As the edge of the sheet is carried over the feeder the roller 29 comes down upon the sheet and thereafter the continued rotation of roller 10 70 causes rotation of roller 29 and forwarding of the sheet between these two rollers.

It will be seen that by reason of the special construction of the feed-board involving making that board in two parts, one of which is stationary and the other adapted for rocking movement, only the forward edge of the sheet-pile is moved vertically in each operation of the apparatus. By reason of this rocking of but a part of the feed-board and moving but a portion of the sheet-pile rather than the whole of the feed-board and the whole of the sheet-pile, less power is required to drive the apparatus and the operation of the apparatus is more 80 smooth. This construction and arrangement of the parts of the feed-board is particularly desirable in a machine specially constructed so that the movement of the forward end of the sheet-pile is the same regardless of the thickness of the pile, for then this movement need only be great enough to carry the top sheet of the pile a very small distance away from the feeder 10. 85

The part 12 of the feed-board is provided 90 with guides for coaction with the edges of the pile of sheets so as to locate the pile upon the feed-board. For this purpose the board has a strip of sheet-metal 37 secured thereto and extending across the feed-board. This strip is bent so that the end-portions 38 thereof are slightly above the surface of the feed-board as shown in Fig. 4. Preferably the intermediate portion of the strip is set 95 into a groove in the board as shown in Fig. 1. The said guides 39 consist of sheet-metal pieces bent to the cross-section shown in Fig. 5 and slotted as shown for the passage of the strip 38. To the outer surface of each side 100 guide are secured two sheet-metal pieces 40 and 41 bent to an angular shape as shown. The laterally projecting portions of these pieces are displaced vertically so that one lies above the strip 38 while the other lies below. The piece 40 has a rectangular opening therein through which the strip 38 passes, the strip fitting snugly within this 105 opening. These laterally projecting portions of the pieces 40 and 41 may be moved toward each other to cause them to grip the strip 38 between them. The outer ends of these portions are connected together on one side of strip 38 by a rivet 42 which lies in engagement with the strip 38. On the other side of strip 38 a screw 43 is provided, projecting upwardly from the lower piece 40 and through an opening in the upper piece 41. A hand nut 44 is provided on the threaded portion of this screw and by 110 tightening this the two parts 40 and 41 may 115 120 125 130

be brought together with sufficient pressure so that they will grip the strip 38 and hold the guide stationary with respect to strip 38 and hence with respect to the feed-board. It will be noted that since the strip 38 fits tightly in the opening in the piece 40 and since the rivet 42 and screw 43 lie in engagement with the edges of the strip 38 the guide 39 cannot move angularly with respect to strip 38. The side guides 39 may therefore be moved toward and away from each other at will, but will be maintained in parallel relation at all times. When the desired position of these side guides has been reached they may be locked in that position by tightening the screw 44. An end guide 45 is provided which is identical in construction with the side guides above described. This end guide is adapted to move lengthwise of the feed-board upon a strip 46 which is secured at its ends to the feed-board and passes over the strip 37 as shown in Fig. 1.

What I claim and desire to secure by Letters Patent is as follows:

- 25 1. In a sheet-feeding apparatus, the combination of a feedboard formed in two parts having their upper surfaces in substantial alinement and one of which parts is pivotally mounted near the edge thereof which is adjacent to the other part, a rotatable feeder overlying the free end of the pivotally mounted part of the feedboard, and means for rocking the pivotally mounted part of the feedboard to carry the top sheet of the pile on the feedboard into and out of contact with the under side of the feeder, substantially as set forth.
- 30 2. In a sheet-feeding apparatus, the combination of a feedboard formed in two parts
- 35

having their upper surfaces in substantial 40 alinement and one of which parts is relatively stationary and substantially horizontally disposed, means for pivotally mounting the other part of the feedboard to rock about an axis adjacent to the adjacent edges of the 45 parts of the feedboard, a rotatable feeder overlying the free end of the pivoted part of the feedboard, a roller movable toward and away from the upper surface of the feeder, a rotatable cam, and means actuated by said 50 cam for rocking the pivoted part of the feedboard to carry the pile thereon into and out of contact with the under side of the feeder, substantially as set forth.

3. In a sheet-feeding apparatus, a feed- 55 board, a strip secured to the upper face thereof and lying parallel to but spaced from said upper face, a guide movable upon said strip and having a wall disposed perpendicular to the surface of the feed- 60 board, which wall is provided with an opening through which the strip passes, two sheet-metal pieces secured to said wall, projecting laterally therefrom and lying one 65 above and the other below said strip, a connection between said pieces on one side of the strip, and a clamping device extending between said pieces on the other side of the strip for drawing said pieces together to 70 cause them to grip said strip, substantially as set forth.

This specification signed and witnessed this 15th day of July, 1913.
